UNITED STATES PATENT OFFICE.

JULIUS J. KARGES, OF JACKSON COUNTY, MISSOURI.

FRictional CLAMPING DEVICE.

1,174,323.

Specification of Letters Patent.

Patented Mar. 7, 1916.

Application filed June 30, 1915. Serial No. 37,356.

To all whom it may concern:

Be it known that I, JULIUS J. KARGES, a citizen of the United States, residing in Jackson county, in the State of Missouri, have invented a certain new and useful Improvement in Frictional Clamping Devices, of which the following is a specification.

My invention relates to improvements in frictional clamping devices.

10 It is particularly adapted for use in connection with display stands which employ sliding members for supporting goods to be displayed.

My invention provides further a novel display stand which may be readily adjusted to suit the purposes for which it may be employed, which is cheap to manufacture, is light in weight, which is durable and which is not liable to get out of order.

20 The novel features of my invention are hereinafter fully described and claimed.

In the accompanying drawing which illustrates the preferred embodiment of my invention, Figure 1 is a perspective view of my improved display stand provided with two of my improved frictional clamping devices. Fig. 2 is a side elevation of one of my improved clamping devices detached from the stand. Fig. 3 is a view similar to Fig. 2 showing a rod held clamped between the members of my improved clamping device. Fig. 4 is an enlarged longitudinal vertical sectional view of an end portion of my improved clamping device.

35 Similar reference characters designate similar parts in the different views.

1 designates the base of the display stand, 2 a tubular standard secured to and extending upwardly therefrom, 3 a vertical stem 40 slidable in the standard 2, and having a lateral arm 4 secured to one side of a rectangular wire frame 5 which is horizontally disposed.

Mounted on the frame 5 are one or more 45 of my improved clamping devices, each comprising two resilient members, preferably consisting of two flat spring bars, of steel or other suitable material, designated respectively by 6 and 7. The end portions of the 50 bar 6 are reversely bent to form inwardly extending arms 8, disposed on the same side of the bar 6 and provided respectively with means slidably engaging the adjacent ends respectively of the bar 7. Such means preferably consists of two pins 9 which extend through holes provided therefor in the bar 6

and through holes provided therefor in the arms 8 respectively. The bar 7 near its ends is provided with two holes through which the pins 9 respectively extend. 60

The ends of the bar 7 are disposed between the bar 6 and the arms 8 and are respectively adapted to be moved longitudinally relatively to said pins.

The inner ends of the arms 8 normally 65 bear against the adjacent side of the bar 7, the latter being bow shaped and having its convex side bearing, adjacent to the middle of the bar, against the adjacent side of the bar 6, which is, preferably, also bow shaped 70 and has its convex side against the bar 7, as shown in Fig. 2.

As shown in the drawing, the bar 7 adjacent to its ends, and adjacent to where it bears against the ends of the arms 8, is bent 75 toward the bar 6.

By means of the construction just described, when a wire or rod of the proper diameter is inserted transversely, as the rod or wire 10 in Fig. 3, it may be slid between the bars 6 and 7 from one pin 9 to the other pin 9, and at all points between said pins will be held clamped by the bars 6 and 7 with substantially the same spring pressure. This permits the clamping device to 85 be slipped onto the frame 5, as shown in Fig. 1, and to firmly clamp said frame in any position thereon to which the clamping device may be adjusted longitudinally or laterally. At the same time the yielding clamping 90 pressure permits of the easy and quick adjustment of the clamping device to the position desired.

By providing two clamping devices mounted on the frame 5, as shown in Fig. 1, 95 they may serve as two oppositely extending arms for supporting the goods to be displayed.

The arms 8 are preferably inclined toward their ends and toward the body of the member 6, and their ends bear upon the member 7 at points 11, respectively at substantial distances from the ends of the member 7, so that too great a pressure will not be exerted against the rod or wire 10 when it is forced past said points 11 to positions adjacent to the pins 9. The end portions of the member 7 are preferably inclined from said points 11 toward their ends and toward the body of the member 6 so that such end portions may exert sufficient pressure upon the rod or wire 10. 110

With the construction described, the rod or wire 10 or the frame 5 will be clamped by a substantially uniform pressure in any position to which it may be adjusted.

5 While I have shown the pins 9 as employed for attaching the members 6 and 7 together, other suitable means may be employed.

10 I have shown the clamping device as forming a part of a display stand, but it is obvious that it may be put to many other uses where it is desired to obtain a uniform sliding clamping engagement of the device with another article.

15 I do not limit my invention to the structure shown and described, as modifications, within the scope of the appended claims, may be made without departing from the spirit of my invention.

20 What I claim is:—

1. A frictional clamping device comprising a resilient clamping member having at its ends arms inwardly turned at one side of said member and spaced apart therefrom, 25 and a second resilient clamping member normally bearing between its ends against the first named clamping member and having its ends respectively disposed between said arms and the first named clamping member, the ends of said arms normally bearing against the second clamping member intermediate of the ends thereof.

2. A frictional clamping device comprising a resilient clamping member having 35 two arms, one at each end, inwardly turned at one side of said member and spaced apart therefrom, a second resilient clamping member normally bearing intermediate of its ends against the first named clamping member and disposed between said arms and the first named clamping member and normally bearing intermediate of its ends against said arms, and securing means for holding the two members attached to each other and 40 relative to which one of said members is transversely movable.

3. A frictional clamping device comprising a resilient clamping member having 50 two arms, one at each end, inwardly turned at one side of said member and spaced apart therefrom, a second resilient clamping member normally bearing intermediate of its ends against the first named clamping member and disposed between and bearing 55 against said arms, and two pins extending transversely through the first named member and through said arms respectively and upon which the second named member is slidably mounted adjacent to its respective 60 ends.

4. A frictional clamping device comprising 65 two spring members adapted to receive between them the article to be clamped and disposed side by side, one of the members having its end portions reversely turned on

the same side and embracing the other member and adapted to bear thereupon at points respectively at substantial distances from the ends thereof.

5. A frictional clamping device comprising 70 two spring members disposed side by side and adapted to clamp between them the article to be clamped, one of said members having opposite end portions reversely turned on the same side and inclined toward the body of said member and embracing the other member and adapted to bear thereupon 75 at points respectively at substantial distances from the ends thereof.

6. A frictional clamping device comprising 80 two spring members disposed side by side and adapted to clamp between them the article to be clamped, one of said members having opposite end portions reversely turned on the same side and embracing the other member and adapted to bear thereupon 85 at points respectively at substantial distances from the ends thereof, said other member inclining from said points toward the body of the opposing member. 90

7. A frictional clamping device comprising 95 two spring members disposed side by side and adapted to clamp between them the article to be clamped, one of said members having opposite end portions reversely turned on the same side and inclining toward the body of said member and embracing the other member and adapted to bear thereupon at points respectively at substantial distances from the ends thereof, said other member inclining from said points toward the body of the opposing member. 100

8. A frictional clamping device comprising 105 two bow spring members disposed side by side with their convex sides adjacent to each other and adapted to clamp between them the article to be clamped, one of said members having opposite end portions reversely turned on the same side and embracing the other member and adapted to bear thereupon 110 at points respectively at substantial distances from the ends thereof.

9. A frictional clamping device comprising 115 two bow spring members disposed side by side with their convex sides adjacent to each other and adapted to clamp between them the article to be clamped, one of said members having opposite end portions reversely turned on the same side and embracing the other member and adapted to bear thereupon 120 at points respectively at substantial distances from the ends thereof, said other member inclining from said points toward its ends and toward the opposing member. 125

10. A frictional clamping device comprising 130 two bow spring members disposed side by side with their convex sides adjacent to each other and adapted to clamp between them the article to be clamped, one of said

members having opposite end portions reversely turned on the same side and embracing the other member and adapted to bear thereupon at points respectively at substantial distances from the ends thereof, said end portions inclining toward their ends and toward the body of the member of which they are portions.

11. A frictional clamping device comprising two bow spring members disposed side by side with their convex sides adjacent to each other and adapted to clamp between them the article to be clamped, one of said members having opposite end portions reversely turned on the same side and inclining toward the body of said member and embracing said other member and adapted to bear thereupon at points respectively at substantial distances from the ends thereof, said other member inclining from said points respectively at substantial distances points toward the body of the opposing member.

12. A frictional clamping device comprising two spring members disposed side by side and movable toward and from each

other and adapted to clamp between them the article to be clamped, one of said members having two arms adapted to bear against the side of the other member which is distant from the body of the member having the arms at points respectively at substantial distances from the ends of the said other member.

13. A frictional clamping device comprising two bow spring members disposed side by side with their convex sides adjacent to each other and movable toward and from each other and adapted to clamp between them the article to be clamped, one of said members having two arms adapted to bear against the other member at points respectively at substantial distances from the ends of said other member and against the distant side of said other member.

In testimony whereof I have signed my name to this specification in presence of two subscribing witnesses.

JULIUS J. KARGES.
